UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed February 27, 1931. Serial No. 518,704.

This invention relates to car roofs of the all-steel, riveted-up type wherein the roofing sheets extend from side plate to side plate and are rigidly secured thereto and to each other to form a rigid load sustaining structure. The principal object of the present invention is to provide a strong and durable waterproof roof of simple construction which can be cheaply manufactured and easily assembled. Other objects are to provide the roof with insulating air spaces and to provide an insulating lining for the underside of the roof. The invention consists principally in increasing the strength and rigidity of the roof by means of upper and lower sheets that are rigidly secured together and to the side plates; it also consists in shaping and arranging the lower sheets to provide air insulating spaces therein; it also consists in securing an insulating lining to the underside of the roof; and it also consists in the construction and arrangements of parts hereinafter described and claimed.

In the accompanying drawings, wherein like symbols refer to like parts wherever they occur,

Fig. 1 is a plan view of a portion of the car roof embodying my invention,

Fig. 2 is an enlarged vertical transverse cross-section through one-half of the roof on the line 2—2 in Fig. 1,

Fig. 3 is a vertical longitudinal cross-section through the roof on the line 3—3 in Fig. 1,

Fig. 4 is a vertical cross-section similar to Fig. 3, showing one of the seams on an enlarged scale; and

Fig. 5 is a vertical transverse cross-section through the eaves portion of the car, the section being taken through one of the seams on the line 5—5 in Fig. 1.

According to the present invention, the metal roof comprises upper and lower roof sheets 1 and 2, respectively, which are pitched or arched from side plate 3 to side plate 3 and have their ends turned down and rigidly secured together and to the outer faces of the upstanding inner flanges 4 of said side plates by rivets 5. The upper roof sheets 1 comprise flat sheets that are overlapped along their

adjacent side marginal portions and rigidly secured together by rows of rivets 6. The lower roof sheets 2 have their adjacent side marginal portions offset upwardly, as at 7, beneath the overlapped side marginal portions of the upper sheets 1. The upwardly offset side marginal portions 7 of adjacent lower roof sheets 2 are overlapped and rigidly secured together and to the overlapped side marginal portions 7 of adjacent upper roof sheets 1 by the rows of securing rivets 6. By this arrangement, the lower roof sheets 2 are connected along their adjacent side margins by inverted channel-shaped upstanding stiffening ribs or seams 8, which serve to space the main body portions of the lower sheets from the upper roof sheets, thereby forming a series of air insulating spaces 9 that extend from side to side of the car between said upper and lower roof sheets and are spaced apart by said hollow seams that connect together the lower roof sheets. The air spaces 9 between the upper and lower series of roof sheets are closed at the ends of the eaves of the car by the downturned eaves end portions of the upper roof sheets. The upper roof sheets 1 are preferably made of galvanized metal, while the lower roof sheets 2 are, for sake of economy, preferably made of sheets of black iron.

Located within the hollow seams or ribs 8, which connect the lower roof sheets 2 together and to the upper roof sheets 1, are wooden filler strips 10 which extend substantially from end to end of said seams and thus serve as stiffeners to increase the strength and rigidity thereof. Said stiffeners also serve as a means for attaching an insulating lining 11 to the underside of the roof. The insulating lining 11 is preferably secured to the bottoms of the filler strips 10 by means of nails 12. The filler strips 10 are preferably detachably secured within the hollow ribs or seams 8 of the lower roof by means of carriage bolts 13 that are suspended from straps or clips 14 located inside of said ribs or seams and secured to the top walls thereof by the securing rivets 6 therefor. These bolt holder clips 14 of the seams 8 are located adjacent to the ridge and the eaves with their ends

riveted flatwise to the undersides of said seams. The clips are perforated intermediate their ends to receive the bolts 13 and have their perforated portions offset downwardly, 5 as at 15, to accommodate the head of said bolts. The upper surfaces of the fillers 10 are notched as at 16 to accommodate the bolt holders 14 and also have bolt holes extending therethrough from top to bottom thereof that 10 are enlarged at their lower ends to accommodate the nuts on the lower ends of the bolts 13.

Running boards 17 extend longitudinally of the car at the ridge and are supported on the top flanges of Z-bar running board 15 saddles 18, whose base flanges rest on the overlapped portions of the upper roof sheets and are rigidly secured thereto by the rivets 6 that secure said portions together.

By the arrangement described, a considerable amount of metal is massed in the upper portion of the roof where it operates to increase the load carrying capacity of the roof. The roof is further stiffened and strengthened by the hollow box girders formed between the 25 seams that connect together the lower series of roof sheets; and said box girders also form air insulating spaces between the upper and lower roof sheets. The hollow seams also serve to accommodate the nailing strips for 30 the wooden lining, which operates to further insulate the roof; and these nailing strips also serve to further increase the strength and rigidity of the roof.

Obviously, my invention admits of considerable modification in the design of hollow seams that connect the lower roof sheets, and I do not wish to be limited to the specific design illustrated.

What I claim is:

40 1. A car roof consisting of upper and lower roof sheets connected along their adjacent side margins by rigid seams, and constituting a self-supporting structure, each seam comprising a single row of rivets extending through two upper sheets and two lower sheets.

50 2. A car roof comprising upper and lower roof sheets that extend from eaves to eaves of the car and constitute a self-supporting structure, said upper sheets being connected together and to said lower sheets along their adjacent side margins by rigid seams the lower sheets having upturned side margins and each seam comprising a single row of rivets.

55 3. A car roof comprising upper and lower roof sheets that extend from eaves to eaves of the car and constitute a self-supporting structure, said upper sheets having their adjacent margins overlapped, and said lower sheets being connected along their adjacent margins by upstanding seams, said seams being located beneath and rigidly secured to the overlapped margins of said upper sheets.

60 4. A car roof comprising upper and lower roof sheets that extend from eaves to eaves

of the car and constitute a self-supporting structure, said upper sheets having their adjacent margins overlapped, and said lower sheets being connected along their adjacent margins by upstanding seams, said seams being located beneath and rigidly secured to the overlapped margins of said upper sheets, the eaves end portions of said upper sheets being bent downwardly over the eaves ends of said lower sheets. 70

75 5. A car roof comprising series of upper and lower roof sheets that extend from eaves to eaves of the car and are rigidly connected together along their adjacent side margins and constitute a self-supporting structure, 80 the sheets of one of said series having ribs formed therein that bear against the sheets of the other series and serve to space apart portions of the sheets of the two series.

6. A car roof comprising upper and lower 85 roof sheets that extend from side plate to side plate with their ends turned down and riveted together and to said side plates and constitute a self-supporting structure, said upper sheets being rigidly connected along 90 their adjacent margins, and said lower sheets having upwardly offset side marginal flanges secured to the undersides of said upper sheets.

7. A car roof comprising upper and lower 95 roof sheets that extend from side plate to side plate with their ends turned down and riveted together and to said side plates and constitute a self-supporting structure, said upper sheets being made of galvanized metal and rigidly connected along their adjacent margins by seams, and said lower sheets being 100 made of black iron and having upwardly offset side marginal flanges secured to the undersides of said upper sheets along their connecting seams. 105

8. A car roof comprising upper and lower sheets that extend from side plate to side plate and have their ends turned down and rigidly secured together and to said side plates, said upper sheets having their adjacent margins overlapped, said lower sheets having their adjacent margins overlapped and offset upwardly beneath the overlapped margins of the upper sheets, and means for 110 rigidly securing together the overlapped margins of the upper and lower sheets. 115

9. A car roof comprising upper and lower sheets that extend from side plate to side plate and have their ends turned down and rigidly secured together and to said side 120 plates, said upper sheets having their adjacent margins overlapped, said lower sheets having their adjacent margins overlapped and offset upwardly beneath the overlapped margins of the upper sheets, means for rigidly securing together the overlapped margins of the upper and lower sheets, the upwardly offset overlapped side marginal portions of the lower sheets forming downwardly opening ribs, filler strips in said ribs, and 125 130

an insulating lining located beneath said roof and secured to said filler strips.

10. A car roof comprising upper and lower sheets that extend from side plate to side plate with their ends turned down and riveted together and to said side plates, said upper sheets having their adjacent margins overlapped, and said lower sheets having their adjacent side margins upwardly offset and overlapped directly below the overlapped margins of the upper sheets and secured thereto by rivets extending through the lapped margins of two upper sheets and two lower sheets, the overlapped upwardly offset margins of said lower sheets cooperating to form downwardly opening channels, wooden filler strips in said channels, and an insulating lining located beneath said roof and secured to said filler strips.

20. 11. A car roof comprising upper and lower roof sheets adapted, arranged and secured together at their side margins to form hollow dead air insulating spaces separated by downwardly opening channels in the underside of said roof the securing means being units that extend through two upper sheets and two lower sheets.

30. 12. A car roof comprising upper and lower roof sheets adapted, arranged and secured together at their side margins to form hollow dead air insulating spaces separated by downwardly opening channels in the underside of said roof, filler strips in said channels, and an insulating lining located beneath said roof and secured to said filler strips.

35. 13. A car roof comprising upper and lower roof sheets that extend from eaves to eaves of the car at different levels with the margins of adjacent upper sheets overlapping each other and with the margins of adjacent lower sheets offset upwardly and overlapping each other below the overlaps of the upper sheets respectively, the upper and lower sheets being secured together by rivets that extend through both the overlaps of the upper and the lower sheets.

Signed at New Kensington, Pennsylvania,
this 20th day of February, 1931.

CHARLES DAVID BONSALL.
